CLAIM

The ornamental design for a baseball shaped transparency viewer, as shown and described.

DESCRIPTION

FIG. 1 is a rear perspective view of a baseball shaped transparency viewer showing my new design;

FIG. 2 is a front perspective view thereof;

FIG. 3 is a front elevational view thereof;

FIG. 4 is a rear elevational view thereof;

FIG. 5 is a left side elevational view thereof, the undisclosed right side being a mirror image thereof; and,

FIG. 6 is a top plan view thereof.

1 Claim, 2 Drawing Sheets

FIG. 1.

FIG. 2.

FIG. 3.

FIG. 4.

FIG. 5.

FIG. 6.
